UNITED STATES PATENT OFFICE.

WESTLEY L. GREIDER, OF STRASBURG, PENNSYLVANIA.

BALING-PRESS.

1,090,614.

Specification of Letters Patent. Patented Mar. 17, 1914.

Application filed April 10, 1913. Serial No. 760,270.

To all whom it may concern:

Be it known that I, WESTLEY L. GREIDER, citizen of the United States, residing at Strasburg, in the county of Lancaster and 5 State of Pennsylvania, have invented certain new and useful Improvements in Baling-Presses, of which the following is a specification.

This invention relates to improvements in 10 baling presses, designed particularly for baling cotton, hay, paper, &c., the general principle of operation involving the compressing action of an upwardly moving plunger or piston.

15 The invention has for its object, principally, to provide for baling or compressing the contents of the baling chamber at an even, slow, steady compressing action to allow amply for the escape of the air and 20 thus avoid distorting the forming bale.

Further objects are to economize space, to lessen the amount of power required to perform the desired work, to promote simplicity of construction, and to otherwise provide 25 for securing approved and effective results conducive to the ends had in view by my invention.

The invention, therefore, consists of certain instrumentalities and features substantially as hereinafter fully disclosed and defined by the appended claims.

In the accompanying drawings is illustrated the preferred embodiment of my invention wherein it will be understood that 35 various changes and modifications may be made therein as to the detailed construction and arrangement of the parts without departing from the spirit of the invention, and in which drawings:

40 Figure 1 is a central vertical longitudinal section of my baling press. Fig. 2 is an end elevation of the same. Fig. 3 is a central vertical transverse section of the device. Fig. 4 is a fragmental partly sectional and 45 partly plan view taken on the line $y-y$ of Fig. 2. Fig. 5 is a partly side and partly sectional view showing the plunger actuating gear and worm equipped shaft engaging said gear, together with the shaft retaining 50 dog, a portion of the housing being broken away. Fig. 6 is a vertical section taken on line 2-2 of Fig. 5, one of the guides for the worm and gear and the shaft actuated by said gear being partly shown. Fig. 7 is a 55 horizontal section taken on the line 3-3 of Fig. 1.

In carrying out my invention I employ a suitable chamber or box 1, preferably of oblong or rectangular general outlines, as disclosed, it being provided with a suitable top or closure 2 furnished upon its under side with spaced apart slats 3; also within this box or chamber is provided a plunger or piston 4 having a solid or imperforate surface, also equipped with like spaced apart slats 5, upon its upper side, the well understood purpose of which spaced apart slats upon both the top or closure and the piston or plunger is to provide for the convenient wiring of the forming bale or contents of the chamber or press. The top or closure 3 is sufficiently depressed or let into the upper end of the box or chamber 1 for the insertion or introduction of one of its ends into a slot or opening 6 in an end wall of the 75 box or chamber. The lateral edges of the opposite end wall of the box are recessed from its upper end downwardly suitable distances to receive and provide for the pivoting of the vertical portions or legs of a bail-like member or keeper 7 with its horizontal or yoke-like portion upstanding beyond the upper end of said end wall, thus providing for the reception thereunder of the corresponding end of the top or closure, as seen 85 in Figs. 1 and 2, said keeper being retained in upright position and automatically returned to such position after the removal of pressure therefrom by means of the resilient member or spring 7^a suitably secured to the 90 box or chamber. Said end of the top or closure 2 is notched or recessed, as at 8, about centrally; and upon said top or closure is eccentrically fulcrumed, as at 9, a cam lever 11, itself having a tooth or projection 12 at 95 its lower corner edge, taking under the bail-like member 7, said cam lever being fulcrumed with its said corner edge let into said recess or notch, whereby, as will be seen from Figs. 1 and 2, by suitably actuating 100 said cam lever it is caused to forcibly secure or retain the top or closure in effective or clamped position, as is apparent.

It will be noted that, when it may be desired to remove the closure or top 2, the cam lever 11 is moved to upright position, whereby its cam surface or edge 11^a will engage and force the bail-like member or keeper 7 outwardly out of engagement with said closure or top, allowing the opposite end of the 110 latter to be withdrawn from the opening 6 of the box or chamber, and accordingly the

- ready displacement of the closure or top. The box or chamber 1 also has its side walls substantially bisected, the upper resulting sections 1^a being hinged, as at 1^b, to allow of the 5 downwardly and outwardly folding or opening of the same for suitable access to the upper portion or half of the box or chamber into which the contents thereof have been finally carried or compressed by the piston 10 or plunger, for suitably or conveniently wiring said compressed mass, as in forming the bale. Suitable latches 1^c pivoted to the end walls of the box or chamber 1 and engaging notched bars or catches 1^d secured to the side 15 walls of the chamber provide for the retention of the door forming sections 1^a in closed position, or as continuations of the lower sections or halves of the lateral walls of the chamber or box 1.
- 20 The plunger or piston 4 has end depending members or boards 5^a, the same being fixed to the under side thereof and equipped near their lower ends with anti-frictional rolls or bearings 13 engaging the lateral 25 walls of the chamber or box 1, said arrangement also providing against any lateral movement of said plunger or piston and consequently any binding action thereof upon the opposite walls of the chamber or box.
- 30 Said plunger or piston is actuated by a horizontal shaft 14, rectangular in cross section, and fitted with sleeves 15, having corresponding bores or interiors with the cross 35 sectional outline of said shaft, said sleeves being received within circular apertures 16 in the depending end members 5^a of the plunger or piston. Said sleeves 15 have fixed thereto, or integral therewith, spur 40 pinions 17 which are received within vertical, longitudinal or elongated slots 18 in the end walls of the chamber or box 1, the walls of 45 said slots, however, being out of contact with said pinions, the function of which pinions will presently appear.
- 45 Guide members 19 and 20 are suitably secured to the outer surfaces of the end walls of the box or chamber 1, one of said guide members upon each end wall being equipped with a plurality of continuous 50 teeth 21, forming a rack, the racks thus provided facing or being opposed to the edge of the opposite plane guide member and engaged by the spur pinions 17 to provide in connection with other means later described 55 for the actuation of the plunger or piston.
- Housings or brackets 22, 22^a receive and 60 form bearings for sleeves 15 of the shaft 3 held at its ends as usual by pins as shown, said sleeves being rotatably supported therein and also carried or moved vertically thereby in effecting the actuation of the plunger or piston, said brackets or housings also practically forming hangers for the shaft and its sleeves, the hanger 22 having 65 preferably, only at its upper corners, and at a lower corner, right angled inwardly extending notched or slotted terminals or studs 23, the slots or notches 23^a of which terminals or studs receive outturned or offset terminals or ribs 24 of the guide members 70 75 80 85 90 95 100 105 110 115 120 125 130 members 19. The other housing or hanger 22^a, however, has only, at an upper corner, a slotted or notched inturned or right angled stud or terminal 23, only one being required for the guidance of that end of the shaft 3, 75 as will be noted by referring to Figs. 1 and 7, the notch or slot of said stud or terminal receiving an outturned offset terminal or rib 25 on a single guide member 19. Also carried by one of the sleeves 15 and housed within the hanger or bracket 22 is a concave faced gear wheel 26, with which meshes a worm 27, fixed upon a handle equipped actuating shaft 28, its handle being designated as 29, said shaft being journaled or supported in said housing or bracket, and by means of which arrangement it will be noted that, by suitably actuating said shaft, the handle 29 being properly grasped, the plunger or piston 4 may be actuated or moved upwardly, effecting thereby the compressing of the contents of the chamber or box 1, the latter having been suitably charged through its feeding opening at the upper end with the required material, as cotton, hay, paper or other balable material, the compressing action of the plunger or piston forcing the material into a compact mass in the upper part of the chamber or box, as is apparent, where it is readily accessible for wiring, as before indicated.
- The housing or hanger 22 has at its upper end an arcuate slotted upward extension 30, its concavity being presented inwardly, it thus being caused to somewhat overhang the 105 housing or hanger 22, as seen particularly in Fig. 5. From the upper end of this extension is pivotally hung a correspondingly outlined latch or dog 31 adapted to be swung in a direction laterally thereof into contact 110 or engagement with the shaft 28, the slot of said extension designated as 33 receiving said shaft, thus providing for the retention of said shaft against endwise displacement, the inner end of the shaft being preferably 115 rounded, as at 34, and received or bearing in a cavity 35 within the bracket or housing. The latch 3 is provided with a projection 32 for its convenient manipulation; and by means of the foregoing arrangement it is 120 further observed that the shaft 28 may be moved, with its end 34 still bearing or resting in the cavity or socket 35 in the bracket or housing, upwardly in a diagonal direction within the slot 33 of the housing extension 30, whereby the worm 27 of the shaft 28 may be unshipped or disengaged from the gear wheel or pinion 26, to allow of the plunger or piston, after the formation of the bale, including the wiring thereof, to be 130

quickly or at once run down to initial or lowered position, as called for in the formation of each successive bale.

Among other characteristics of my press, it will be noted that the bale is formed, or, rather, the compressing operation performed, by the upward movement of the plunger, the plunger completing said operation with such upward movement or stroke thereof for the reasons and advantages before recited, while the device in its entirety is extremely simple in construction, of few parts, readily and with the application of the minimum amount of force operated, and effective in its action, aside from being inexpensive of manufacture, &c.

Having thus fully described my invention, what I claim and desire to secure by Letters Patent, is:

1. A baling press, including a plunger or piston, a sleeved shaft carrying said plunger, an actuating shaft geared to said plunger-carrying shaft, vertically movable bearings for said shafts, guides upon the press-box for said bearings, the press-box having racks thereon, said sleeved plunger-carrying shaft being geared to said racks.

2. A baling press, including a plunger or piston, a baling chamber containing the latter, a shaft carrying said piston or plunger, an actuating shaft, intergeared worm and gear effecting connection between said piston carrying shaft and said actuating shaft, and slideable bearings for said actuating and piston carrying shafts, said intergeared worm and gear controlling said shaft.

3. A baling press, including a piston or plunger, a shaft with sleeves thereon, said sleeves carrying said plunger and equipped with pinions, an actuating shaft geared to the aforesaid shaft, racks provided upon walls of the baling chamber, slideable bearings for said shafts forming housings for said gears, said pinions gearing with said racks.

4. A baling press, including a baling chamber having a plunger, a shaft equipped with sleeves, themselves having pinions, slideable bearings for said shaft sleeves, said baling chamber being equipped with guide members, one upon each end wall of said chamber, said chamber end walls having vertical slots, one wall of each slot having a rack thereon, said pinions meshing with

said racks, and a handle equipped shaft, 55 worm and gear wheel connection between said latter shaft and the aforesaid shaft, one of said slideable bearings also carrying said handle-equipped shaft.

5. A baling press, including a baling chamber, a plunger within said baling chamber, a shaft equipped with sleeves bearing said plunger, said sleeves being provided with pinions, said baling chamber having vertical slots in its end walls, one wall of 65 each slot being provided with a rack, said pinions meshing with said racks, slideable housings or hangers, guiding members upon the end walls of said baling chamber for said housings, one of said housings being 70 provided with an arcuate slotted upward extension having pivotally hung therefrom a latch or dog adapted to swing in a direction at right angles with respect to said extension, said housing also having at its end 75 opposed to said upward extension and said dog a cavity, an operating shaft having one end rounded and received by said cavity, said shaft extending through the slot of said upward extension and engaged by said 80 pivotally hung latch or dog, and a gear wheel and worm connection between said operating shaft and one of said shaft carried sleeves.

6. In a baling press, including a baling chamber, means arranged in connection therewith for effecting the baling operation, a closure for said baling chamber, one end thereof being received within an end wall of said baling chamber, the opposite end 90 wall of said chamber having an automatically held pivoted bail-like member at the upper end, extending above said upper end, and a cam lever or dog fulcrumed upon said closure, one end of said closure being received within said bail-like member and having a recess therein to receive the forward end of said cam lever, the cam edge of said 95 cam lever being adapted to engage and force said bail-like member off said end of said closure.

In testimony whereof I affix my signature in presence of two witnesses.

WESTLEY L. GREIDER.
